COMBINED PHOTOGRAPHIC CAMERA AND STROBE

Cooper C. Woodring, Plandome, and Ronald Emmerling,
New City, N.Y., and Michael Boehm, Green Farms,
Conn., assignors to J. C. Penney Co., Inc., New York,
N.Y.

Filed June 26, 1974, Ser. No. 483,395

Term of patent 14 years

Int. Cl. D16—01

U.S. Cl. D16—6

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 13

FIG. 14

FIG. 15FIG. 1 is a front perspective view of a combined photographic camera and strobe showing our new design; FIG. 2 is a top plan view thereof;

FIG. 3 is a front elevational view thereof;

FIG. 4 is a left side elevational view thereof;

FIG. 5 is a right side elevational view thereof;

FIG. 6 is a bottom plan view thereof;

FIG. 7 is a rear elevational view thereof;

FIG. 8 is a front perspective view of the strobe member, the camera member being omitted for ease of illustration;

FIG. 9 is a front elevational view thereof;

FIG. 10 is a right side elevational view thereof;

FIG. 11 is a top plan view thereof;

FIG. 12 is a bottom plan view thereof;

FIG. 13 is a rear elevational view thereof;

FIG. 14 is a left side elevational view thereof;

FIG. 15 is a front elevational view of FIG. 1 showing a second embodiment of the light sensing means of the camera member;

FIG. 16**FIG. 17**FIG. 16 is a front elevational view of FIG. 1 showing a third embodiment of the light sensing means of the camera member; and

FIG. 17 is a front elevational view of FIG. 1 showing a fourth embodiment of the light sensing means of the camera member.

We claim:

The ornamental design for a combined photographic camera and strobe, substantially as shown and described.
